COMBINED PACKAGE AND DISPENSER

Lawrence H. M. Vineburgh, Hartford, Conn.

Application November 12, 1940, Serial No. 365,342

1 Claim. (Cl. 206—56)

This invention relates to packaging and dispensing and more particularly to a combined sanitary cup package and dispenser.

Prior to the instant invention paper cups have been sold for domestic use in packages of various types. These packages have ranged from cartons made of cardboard to ordinary wrapping paper.

It is an object of the instant invention to provide a novel combined package and dispenser which may be readily and inexpensively fabricated of simple and available materials which will serve as a neat package for paper or sanitary disposable cups and which may be readily converted into a dispenser of a character which will dispense one cup at a time as needed while maintaining the remainder in clean and sanitary condition.

It is another object of the invention to provide a combined transparent package and dispenser for paper or other sanitary disposable cups.

Other objects and the nature and advantages of the invention will be apparent from the following description taken in conjunction with the accompanying drawing, wherein:

Fig. 1 is a front view in elevation of a combined package and dispenser in accordance with the invention;

Fig. 2 is a view similar to Fig. 1 with the cups in dispensing relation and with one of the cups substantially totally dispensed shown in dotted lines;

Fig. 3 is a side elevational view of the device shown in Fig. 2.

Referring to the drawing, the combined package and dispenser 10 comprises a body portion 11 which may be fabricated of sheet rubber, paper or other non-rigid or flexible material such as wax paper or transparent flexible plastics. When the body portion 11 is made from sheet material, it may be rolled in the form of a tube so that the edges 12 and 13 overlap and may be joined together by the utilization of cement or in any other suitable manner. When the material of the body portion 11 is of rubber, the edges 12 and 13 may be vulcanized together or joined by the use of rubber cement. When the material of the body portion 11 is a thermo-plastic substance, heat and pressure may be utilized to effect this seal.

The bottom portion 14 of the body 11 is gathered, as shown at 15, and means 16 are provided for holding the bottom or dispensing portion of the package 10 in yieldable gathered relation,

Means 16 may take the form of elastic material of smaller dimension than the circumference of the body portion 11 and such elastic of smaller dimension may be cemented to the body portion 11 at its lower portion 14. The turned over portion 17 adds a decorative touch and at least partially hides the elastic 16 of smaller dimension. The turned over portion 17 also presents a finished reinforced edge at the bottom 14 and serves to prevent tearing of the package as the cups 18 are dispensed.

The stack S of cups 18 may be loaded within the combined package and dispenser 10 either through the top or the bottom, and when they are loaded through the top, the cap 19 is sealed to the top portion 22 of the dispenser 10 after the loading operation. The cap 19 may be fabricated of rubber when the body portion 11 is rubber and the two vulcanized together or otherwise suitably joined to effect a finished combined package and dispenser. The cap 19 may be provided with a ring 20 with which may be associated a decorative string 21 for suitably supporting the combined package and dispenser on a wall whereby the cups may be dispensed by pulling the lowermost cup downwardly as shown by solid and dotted lines in Fig. 2 at the bottom thereof. As the lowermost cup is pulled downwardly, the bottom portion 14 of the dispenser 10 expands and permits the lowermost cup to be removed but catches the next cup and thereby serves to support the stack S within the body portion 11 pending withdrawal of the next cup.

When the device 10 serves as a package, the cups 18 are in the position shown in Fig. 1 and are in non-dispensing relation with the elastic 16 in contracted position. In this position, the cups are protected in a sanitary manner by the combined package and dispenser 10 and no dust or dirt can contaminate the inner portions or the lip portions of the cups. When it is desired that the package serve as a dispenser, the cups 18 are brought into the position shown in solid lines in Fig. 2 with the elastic means 16 in partially expanded position. As the cups 18 are removed, the elastic 16 is stretched to fully expanded position, shown in dotted lines. The pressure of the elastic means on the sides 18a of the cups serves to push the sides toward each other and thereby increase the transverse dimension of the interior of the cup being withdrawn so that it detaches itself from the remainder of the stack, thereby facilitating the dispensing action referred to.

In the operation described, it will be apparent

that the elastic bottom 14 of the package 10 serves as a cam means for increasing the transverse dimension of the cup being dispensed to release it from the remainder of the stack and as a stop means for holding the remainder of the stack within the dispenser pending withdrawal of the next cup.

It will be apparent that the construction described in connection with Figs. 1 to 3, inclusive, of the drawing of this application is extremely desirable and that this ingenious device may serve both as an inexpensive saleable package for stacked paper cups of generally trapezoidal elevation and as a dispenser. Further, the device efficiently protects the cups from dust and dirt and is of such portable nature that it may be carried in the glove compartment of an automobile or in any other very small space and then hung on a tree or any other convenient support so that its use for picnics and the like is desirable. Further the package is of such inexpensive nature that it may be readily disposed of when the stack of cups therein have been used and the user may be assured that the cups will be protected until used.

Not only may the body portion 11 of the package 10 be made of opaque rubber and printed with decorative designs when desired, but it may be made of relatively thin translucent rubber or oiled silk or other material which permits the transfer of light therethrough so that the cups may be more or less visible to some extent when within the package. As the package 10 is relatively non-rigid, the user may also ascertain the relative number of cups by the sense of touch.

It is to be understood that it is within the scope of the invention to close the top portion 22 of the package 10 in other ways than that shown and described and in fact that body portion 11 of the package may be fabricated of one piece with the entire top portion integral and all the gathering occurring along the sides and bottom. When the

device is so fabricated, a cap similar to the cap 19 may be secured to the integral top in any suitable manner as described in order to provide for supporting the package when it is to be used as a dispenser.

It will be obvious to those skilled in the art that various changes may be made in this device without departing from the spirit of the invention and therefore the invention is not limited to what is shown in the drawings and described in the specification but only as indicated in the appended claim.

What is claimed is:

A package-dispenser and cup-stack combination comprising a nested stack of cups located in a housing comprising an elongated body portion fabricated of normally relatively inelastic, flaccid, limp, soft, thin walled material, the cross sectional dimension of said body portion being sufficiently large as compared to the largest cross sectional dimension of the cups so as not to bind the said cups and permit relatively free movement of the cups from the tops of said body portion toward the bottom end of said body portion, said bottom end which is normally open being formed with a gathered edge of ring like configuration and of smaller dimension than the transverse sectional dimension of the body portion of the package, the said bottom edge being elasticized generally uniformly about its periphery to permit the passage of cups therethrough when a pulling force is exerted thereon, the edge of said bottom end being sufficiently elasticized so as to be strong enough to normally hold the cups within the package and fit snugly about the lower portion of the lowermost cup of which the bottom protrudes therethrough, the combined dispenser and cup stack being relatively rigid as compared with the inelastic, flaccid, limp, soft, thin walled material of the package body.
